[57] CLAIM

The ornamental design for a game board, as shown and described.

DESCRIPTION

FIG. 1 is a perspective view of a game board showing my new design;
FIG. 2 is a perspective view thereof on a reduced scale with the game board being partially folded for storage;
FIG. 3 is a perspective view thereof showing the game board completely folded for storage;
FIG. 4 is a top plan view thereof and
FIG. 5 is a top plan view of a second embodiment of the design of FIG. 1.
The bottom plan view of FIGS. 4 and 5 are mirror images of FIGS. 4 and 5 respectively.
